UNITED STATES PATENT OFFICE.

JOHN P. HOPPESCH, OF CHICAGO, ILLINOIS.

HORSESHOE.

No. 842,316.

Specification of Letters Patnt.

Patented Jan. 29, 1907.

Application filed June 22, 1906. Serial No. 322,823.

To all whom it may concern:

Be it known that I, JOHN P. HOPPESCH, a citizen of the United States, and a resident of Chicago, Cook county, Illinois, have invented 5 certain new and useful Improvements in Horseshoes; and I do hereby declare that the following is a full, clear, and exact description of the same, reference being had to the accompanying drawings, and to the letters of 10 reference marked thereon, which form a part of this specification.

This invention relates to improvements in horseshoes, and more particularly to that 15 class of horseshoes adapted to afford a resilient tread.

Heretofore though rubber pads have been used to some extent to reduce concussion and to prevent slipping on asphalt such shoes are not reliable in winter, owing to the accumulations of snow compacted inside of the shoe. 20 This is a serious fault with most shoes and proves very dangerous. Furthermore, the usual types of shoe, either plain shoes or bar-shoes, do not sufficiently protect the frog of 25 the foot, which is likely to be injured by stones wedging into the shoe or by nails which penetrate the frog, disabling the horse.

The object of this invention is to provide a 30 resilient shoe adapted for satisfactory use on asphalt and all other streets and so constructed as to enable worn-out portions of the shoe to be discarded, while permitting those less worn to be retained for future use.

It is a further object of the invention to 35 afford a resilient and practically impervious shield covering the frog to protect the same from injury and filling the shoe and adapted to prevent an accumulation of snow within the shoe.

40 The invention consists in the matters hereinafter described, and more fully pointed out and defined in the appended claims.

In the drawings, Figure 1 is a top plan view of a shoe embodying my invention. 45 Fig. 2 is a bottom plan view of the same. Fig. 3 is a central longitudinal section of the same. Fig. 4 is a section taken on line 4-4 of Fig. 2.

As shown in said drawings, A indicates a 50 horseshoe of steel or other suitable metal or material, provided with a toe-calk a^2 of any suitable kind and the ends or heels of which are relatively short and are recessed on the under side to receive the heel-plate. This is stamped or formed in any suitable manner 55 from a suitable plate to a shape to complete the external contour of the shoe, extending

the same back sufficiently to support the heel, said bar or plates comprising relatively flat wings B, which fit to the end of the shoe A, as shown in Figs. 2 and 4, and on the inner side incline rearwardly to the main body of the plate, which is stamped to afford a transverse external upturned flange b' and an oppositely-disposed internal upturned flange b^2 , providing between the same a chamber or 60 seat to receive the rubber or other resilient bar or pad C. This may be secured in place by riveting to the heel-plate, as shown in Figs. 1 and 2, or by means of pins or wires c, which extend therethrough and engage in the flanges b' and b^2 of said plate, or both the 65 rivets and pins or wires may be employed, if preferred. Said heel-plate is secured in place by means of screw-bolts a^3 , which extend through longitudinally-slotted holes a 70 in the ends of the heel-plate and are threaded into the shoe.

The upper ends of the screws are riveted down on the shoe, and the heads a^4 are shaped to afford supplemental heel-calks, as shown 75 in Figs. 2 and 3, which are of less height than the thickness of the rubber bar or pad.

A resilient pad is engaged within the shoe and positioned to protect the frog. This, as shown, consists of a thick layer D of leather, 80 rawhide, or other suitable resilient but practically impervious material, on which, as shown, is laid a pad d of resilient material, such as rubber, preferably vulcanized on a base fabric d^2 of canvas or other material, to 85 prevent deforming by stretching. On the upper side of said layer D is secured a V-shaped plate d^3 of steel or other suitable material and which is engaged to the pad by means of rivets d^4 , which extend there- 90 through and through all layers of the pad. Said plate d^3 at its apex projects forwardly to engage within and upon the toe of the shoe, and at the rear or heel end of the pad the leather layer D and the ends of said plate extend upon the lateral wings B of the heel-plate, thus affording a positive support both 95 at the front and rear end of the pad when the shoe is nailed to the hoof and filling the shoe, while protecting the frog.

The operation is as follows: The shoe may be of any suitable form and the heel-plate when secured in place with the rubber bar therein affords a transverse cushion which reduces the jar or concussion of the horse's 100 feet when on the pavement or hard road and at the same time prevents slipping. The 105

heel-calks a^4 (the heads of the bolts a^3) remain of considerably less height than the rubber bar or cushion and in consequence are adapted to take the pulling stress when 5 the cushion is compressed, and inasmuch as these wear away more rapidly than the rubber said calks at all times maintain their appropriate height relatively of the rubber cushion, thus insuring a non-slipping contact with the pavement or road.

The shoe may of course be used without the protecting resilient pad below the frog. Where so used, however, the plate d^3 projects forward over the shoe sufficiently to rest on 15 the toe of the shoe and on the heel-plate. The pad can thus never be displaced except by removal of the shoe or the heel-plate and owing to its construction not only protects the frog from injury but prevents stones 20 wedging in the shoe and also the accumulation of snow from balling in the shoe.

Obviously details of construction may be varied without departing from the principles of my invention.

25 I claim as my invention—

1. A horseshoe provided at the heel with a transverse bar removably engaged thereto, a resilient pad engaged to said bar and of approximately the same length, and removable 30 means engaging the bar to the shoe.

2. A horseshoe embracing a short rigid steel shoe, a transverse bar bolted to the heels and affording in its lower face a recess, a cushion bar or pad rigidly secured in said recess and equal in length to said bar and bolts securing said bar in place on the shoe, the heads of said bolts affording calks.

3. A device of the class described embracing a relatively short horseshoe, a transverse 40 steel plate bolted thereto and projecting rearwardly therefrom and affording a channel on the under side thereof, a rubber pad or bar engaged in said channel and wires extending transversely through said pad and engaging 45 the sides of the channel.

4. In a device of the class described a steel plate affording a bottom channel adapted to be engaged to or detached from the shoe, a cushion-bar engaged therein and wires extending 50 transversely through the cushion-bar and engaging at each side of the channel.

5. In a bar-horseshoe a protecting-pad engaged within the shoe to cover the frog, and embracing an inner resilient layer of leather, 55 an outer resilient layer of rubber, a layer of canvas between said resilient layers, a V-shaped metal plate riveted on the inner side of the pad with its apex projecting forwardly

to engage on the toe of the shoe, the rear ends thereof engaging on the pad.

6. In a device of the class described the combination with a shoe of a removable plate engaged to the ends thereof, a resilient pad securely engaged to said plate and extending the entire length thereof, and means 65 engaging the plate and shoe together affording calks for the back of the shoe.

7. In a device of the class described the combination with a shoe of a metallic plate therefor having a channel or recess therein, 70 inwardly-projecting wings on said plate, a resilient pad riveted to the plate, a resilient pad closely fitting the center of said shoe adapted at the rear thereof to rest on said wings and a metal plate securely engaged to 75 the pad adapted to support the same on the toe of the shoe.

8. In a device of the class described the combination with a shoe provided with a toe-calk of a heel-plate adapted to be removably 80 engaged to the shoe and flanged to afford a channel or seat, a resilient pad fitted in said channel, a resilient pad conforming with the inner contour of the shoe and resting at its rear on said wings and a plate engaged to said 85 pad adapted to support the front end thereof.

9. In a device of the class described the combination with a shoe of a metallic heel-plate engaged thereto, a resilient pad riveted and wired to said plate, a protective pad fitted in said shoe and resting on said plate and shoe, said pad comprising a layer of leather, 90 canvas and an outer layer of rubber, a metallic plate engaged to the leather layer and rivets fastening said layers and plates together.

10. In a device of the class described the combination with a shoe having recessed ends, of a plate having inwardly-projecting wings or flanges integral therewith adapted to fit the recessed ends of said shoe, said plate flanged at the sides and back, a resilient pad engaged therein, bolts engaging the plate and shoe together affording calks for the back of the shoe and a resilient pad for the center of 105 said shoe adapted at its rear to rest on said wings and a plate engaged to and projecting from the apex of said pad adapted to support the front end thereof.

In testimony whereof I have hereunto subscribed my name in the presence of two subscribing witnesses.

JOHN P. HOPPESCH.
